UNITED STATES PATENT OFFICE.

THOMAS A. BISSELL, OF BUFFALO, NEW YORK.

CAR-COUPING.

SPECIFICATION forming part of Letters Patent No. 448,406, dated March 17, 1891.

Application filed December 6, 1890. Serial No. 373,756. (No model.)

To all whom it may concern:

Be it known that I, THOMAS A. BISSELL, a citizen of the United States, residing at Buffalo, in the county of Erie and State of New York, have invented new and useful Improvements in Car-Couplings, of which the following is a specification.

This invention relates to that class of car-couplings in which each draw-head is provided with a pivoted coupling-hook having an inwardly-projecting arm or knuckle which engages with a gravity-pawl pivoted in a recess in the draw-head when the coupling-hooks of two adjacent cars are coupled together.

15 The object of my invention is to improve the construction of this class of couplers, whereby the operation of the gravity-pawls in locking the hooks is more reliable and certain, and enabling this class of couplers to be employed on passenger-cars as well as freight-cars.

In the accompanying drawings, Figure 1 is a longitudinal sectional elevation of a draw-head provided with my improvement. Fig. 2 25 is a horizontal section thereof. Fig. 3 is a vertical transverse section in line *x x*, Fig. 1. Fig. 4 is a fragmentary vertical section in line *y y*, Fig. 3.

Like letters of reference refer to like parts 30 in the several figures.

A represents the draw-head, which is provided at its front end with a chamber or recess *a*, in which the coupling mechanism is arranged.

35 *B* represents the horizontally-swinging coupling-hook pivoted on one side of the recess by a vertical bolt *b*, passing through lugs *c c*, projecting forwardly from the side of the draw-head. The hook *B* is provided with an inwardly-projecting knuckle or shank *B'*, which is arranged at right angles to the hook. This knuckle extends into the recess *a* when the hook is in its normal or coupled position, and is held in place by a horizontally-swinging 45 gravity pawl or catch *D*, which engages with its free end against the inner end of the knuckle. The pawl *D* is pivoted in the recess *a* by a bolt *d*, passing through the upper and lower walls of said recess, and is also 50 capable of vertical movement thereon.

e e' represent inclined ribs formed, respect-

ively, on the upper and lower walls of the recess.

In raising the pawl for the purpose of releasing the knuckle of the hook, its upper face 55 strikes the upper inclined rib, which causes the pawl to swing inwardly, whereby the knuckle or shank of the coupling-hook is released and the latter allowed to swing forwardly for the purpose of uncoupling the 60 draw-heads. When the pawl descends it strikes the lower inclined rib, which causes the pawl to swing forwardly into the proper position for locking the knuckle of the coupling-hook when the latter is moved into its 65 normal or coupled position.

F represents a pivoted rocking arm or lever arranged in a suitable opening *f*, formed in the top of the draw-head above the pawl and communicating with the recess *a*. The rocking arm or lever *F* is pivoted to a transverse pin *f'*, extending across the opening *f*, and the gravity-pawl is connected with said lever by a short chain *g*, the upper end of which is pivoted to the lever on one side of the transverse pivot-pin *f'*. The rocking arm or lever *F* is provided on one side of its pivot with a shoulder *h*, which rests against the top of the draw-head when the arm or lever is in its normal position and forms a stop for limiting 70 the rocking movement of the arm or lever. The arm or lever is held in its normal position, with its shoulder *h* against the top of the draw-head, by a spring-bolt *I*, arranged in a vertical recess or socket *i*, formed in the draw-head on the opposite side of the pivot of the rocking arm, and bears with its upper end against a heel or projection *j*, formed on the rocking arm, as shown in Fig. 3. The outer side *j* of the heel *j* is curved concentric with 75 the pivot of the rocking arm, and the upper end or mouth of the vertical socket *i* above the head of the spring-bolt is slightly curved inwardly, so that the upper curved face of the heel fits close to the curved mouth of the 80 socket, whereby dirt, &c., is prevented from entering the socket and interfering with the operation of the spring-bolt. The socket *i* is preferably formed at its bottom with an opening 85 for the escape of any foreign substance 90 that may have lodged in the socket. The opposite end of the slot or opening is closed by 95 100

the shoulder of the rocking arm. When the rocking arm or lever is in its normal position, as shown in Fig. 3, the gravity-pawl is also in its normal position, with its outer end engaging against the knuckle of the coupling-hook.

5 K represents a pull-chain whereby the rocking arm or lever and the pawl are operated for the purpose of releasing the coupling-hook. The pull-chain is pivotally secured with its 10 inner end to the upper end of the rocking arm or lever, and extends laterally from said lever, with its opposite end secured to the lower end of the hand-lever *k*, which is pivoted to the platform or end sill of the car. Upon drawing the pull-chain laterally the rocking arm or lever swings outwardly and raises the pawl, whereby the latter is withdrawn from the 15 knuckle of the coupling-hook. This permits the latter to swing outwardly and uncouple 20 itself from the adjacent draw-head.

As formerly constructed the pull-chain K was connected directly to the gravity-pawl by passing the chain downwardly through the slot or opening in the top of the draw-head and 25 connecting its end with the pawl. This caused considerable friction when the pull-chain passed over the top of the draw-head in drawing horizontally thereon, and the weight of the chain when slack frequently caused the 30 pawl to become disengaged from the hook and allowed the cars to become uncoupled. By employing a rocking arm or lever to transmit the horizontal pull of the chain K to the gravity-pawl, the friction resulting from the use of a 35 side-draft pull-chain is avoided. The tension of the spring-bolt against the rocking arm or lever tends to return the latter to its normal position, whereby the pull-chain is drawn inwardly when the cars have been uncoupled. 40 This keeps the pull-chain taut at all times when not in use, and allows the pawl to descend and resume its proper position preparatory to again interlocking with the coupling-hook.

45 I claim as my invention—

1. The combination, with a draw-head hav-

ing a recess in its front end and a pivoted coupling-hook, of a gravity-pawl arranged in said recess and adapted to interlock with said hook, a rocking arm or lever pivoted to said draw-head and connected with said pawl, and a pull-chain attached to said lever above its pivot, substantially as set forth.

2. The combination, with the draw-head, having a recess in its front end, a pivoted 55 coupling-hook and gravity-pawl arranged in said recess and interlocking with said hook, of a rocking arm or lever pivoted in a slot or opening formed in the draw-head above said recess, a chain connecting the pawl with said 60 lever, and a stop or shoulder formed on said lever to limit its downward movement in said slot, substantially as set forth.

3. The combination, with the draw-head having a recess in its front end, a pivoted 65 coupling-hook, and a gravity-pawl arranged in said recess and interlocking with said hook, of a rocking arm or lever pivoted in said draw-head and connected with said pawl, a 70 stop or shoulder formed on said lever, and a spring whereby the rocking lever is held against said stop, substantially as set forth.

4. The combination, with the draw-head having a recess in its front end and a socket 75 formed in one side of said recess, of a pivoted coupling-hook, a gravity-pawl arranged in said recess and adapted to interlock with said hook, a rocking arm or lever pivoted in a slot or opening formed in the draw-head, a chain connecting said lever with the gravity- 80 pawl, a shoulder formed on one side of the rocking lever, a downwardly-projecting heel formed on the opposite side of said lever, and a spring-bolt arranged in said socket and bearing upwardly against the heel of the 85 rocking lever, substantially as set forth.

Witness my hand this 26th day of November, 1890.

THOMAS A. BISSELL.
